SPOT-SATURATED COMPOSITION BOARD

Eugene C. Knoblock, South Bend, Ind., assignor
to Mastic Asphalt Corporation, South Bend,
Ind., a corporation of Indiana

Application May 1, 1939, Serial No. 271,013

9 Claims. (Cl. 20—5)

This invention relates to spot-saturated composition board, and particularly to such material adapted for use as exterior building covering material.

Composition board, provided with a waterproof and decorative coating, is obtaining increasing public acceptance for use as an exterior building covering material. Asphalt or other bituminous plastic material provides an effective weatherproofing medium for the exterior face of the board, and also constitutes an excellent medium for obtaining adhesion of mineral surfacing particles to provide a decorative masonry-simulating face. Also, the composition board may be provided with a shallow surface saturation to increase its weatherproof qualities. However, building covering members having a composition board base, and particularly masonry-simulating siding members, generally must be nailed at points which are exposed to the weather. Each such exposed nailing point is a potential source of trouble and failure. For example, a nail may be driven too deeply, so that its head fractures the fibrous constituents of the board adjacent its surface and exposes the same to the weather, with the result that the fibers absorb moisture and cause compacted fibers of the board to expand and thus weaken the board and lead to leakage of the board at that point. Also, the mere driving of a nail through the board in proper manner may leave a minute passage around the nail for entry of water therein, as by capillary action by reason of the weakness of the board and the softness thereof which makes it readily penetrable. These conditions pertain despite the best efforts of manufacturers and applicators to avoid them, and despite the quality of waterproofing materials used in manufacture, or care exercised in application. Even the practice of sealing over the nail head with waterproofing during application does not fully solve the problem.

It is, therefore, the primary object of this invention to provide a composition board which is provided with a restricted portion thereof, at which a nail is to be driven, deeply saturated with waterproofing material to rigidify and harden said nailing portion and to waterproof the board around the nail.

A further object is to provide a composition board having a shallow surface saturation of waterproofing material at all surfaces thereof and spaced nailing portions saturated to a depth at least one-half the thickness of the board but

restricted in size to minimize reduction of the insulation values of the board.

A further object is to provide a composition board having a restricted portion thereof deeply saturated from opposite faces thereof. 5

A further object is to provide a novel, simple and inexpensive method of deeply saturating composition board at restricted parts thereof.

Other objects will be apparent from the description and appended claims. 10

In the drawing:

Fig. 1 is a plan view of a building siding member having a composition board base, and illustrating spot-saturated nailing portions in dotted lines. 15

Fig. 2 is a split sectional view of a composition board having spot-saturated nailing portions. 15

Fig. 3 is a fragmentary view illustrating impaling means adapted to penetrate opposite sides 20 of a composition board preparatory to spot-saturation.

Fig. 4 is an enlarged fragmentary sectional view of a composition board with a shallow surface saturation and a restricted portion saturated the full thickness of the board. 25

Fig. 5 is an enlarged fragmentary sectional view of a composition board with a shallow surface saturation and opposite restricted portions deeply saturated from both exterior surfaces. 30

Fig. 6 is an enlarged fragmentary sectional view of a composition board having a restricted portion deeply saturated from only one surface thereof.

Fig. 7 is an enlarged fragmentary sectional view illustrating a spot saturated composition board building covering member nailed to a support. 35

Fig. 8 is a fragmentary sectional view illustrating composition board as in Fig. 5 nailed to a support. 40

Fig. 9 is a fragmentary sectional view of a conventional composition board having a nail driven therethrough.

Referring to the drawing, which illustrates the preferred embodiment of the invention and particularly to Figs. 1 and 7, which illustrate a building covering member, the numeral 10 designates a composition board of compacted fibrous material such as "Celotex," "Insulite" or any like rigid fibrous insulation board. It will be understood, of course, that similar material such as laminated board formed of paper, fibrous sheets or the like may also be considered within the scope of this invention. Board 10 may have a 55

shallow saturation 11 of waterproof material at all surfaces thereof. The outer surface of board 10 is coated with a layer 12 of asphalt or other waterproof plastic material in turn covered with 5 mineral particles or grit partially imbedded therein to firmly adhere thereto and provide a masonry simulating surface. This coating is preferably grooved or depressed at 13 to simulate mortar joint lines outlining masonry-simulating faces or areas 14. The building covering member so formed is secured at a plurality of spaced points thereof to the sheathing or frame 15 of a building by nails 16. A restricted portion 17 of the board at spaced points thereof 10 through which nails 16 are driven is deeply saturated with waterproofing material, such as asphalt. The depth of the saturation is preferably at least one-half the thickness of the board, and portions 17 preferably coincide with one or more 15 of the grooves 13.

The precise character of the saturation portions 17 may vary. Thus in the embodiment illustrated in Fig. 7, a plurality of narrow closely grouped passages 18 are formed in and extend 20 entirely through the board. Thus, when the board is dipped in or otherwise treated with plastic waterproofing material while heated or otherwise conditioned in fluid state, for the purpose of obtaining the surface saturation 11 thereof, 25 said material will flow into and fill the passages 18 and saturate the board around each passage to completely saturate the body at and around the portion thereof having said passages, which saturation will extend the full thickness of the 30 board. The saturated portion so formed will be of a size substantially greater than the thickness of a nail, so that high precision and accuracy in locating the nail, and exact positioning of the nail perpendicular to the board, will not be 35 necessary; but the size is held to a minimum operative for its purpose in order that the insulation value of the board will not be unnecessarily impaired thereby. Some indicating means, such as a small indentation or the like (not shown), 40 will be formed in the coating 12 of the board to guide the applicator in locating said saturated portions. The board is hardened or solidified at portions 17 so that a nail driven therethrough will be firmly anchored therein with a tight 45 waterproof driving fit. Also, the hardened character of portion 17 strengthens the board to give a firm strong connection between the board and its support by means of the nail. Even if water should seep into the interior of the board around 50 the nail, no damage can occur because of the waterproof saturation of the adjacent fibers of the board which prevents penetration to the absorbent unsaturated core of the major portion of the board. Also, the fibers of the board are so 55 firmly bound together by the spot saturation 17 that a nail emerging from the board will not spread and laterally displace the fibers at the emerging surface as conventionally occurs in nailing composition board as illustrated at 19 in 60 Fig. 9.

Other embodiments of spot saturation are illustrated in Figs. 4 and 5, utilizing the apparatus illustrated in Fig. 3 for their formation. This apparatus comprises a pair of plates or supports 20 mounting a plurality of needles or impaling members 21 in closely spaced or grouped relation. These supports are pressed against opposite faces of composition board 10 with the needle groups in opposed or substantially registering position 25 to pierce the board and form recesses 22 therein.

Needles 21 are preferably of a length slightly less than one-half the thickness of the board, and may be shorter, depending upon the depth of spot saturation desired. Needles 21 are thin, and they serve not only to form recesses or holes 22, 5 but also to loosen the compacted fibers there-around and therebetween to increase the absorptive properties of the board at the restricted board portion determined by the number and spacing of the needles impinging therein. When 10 the fibers have thus been loosened, a deep saturation is obtained at the loosened portion incident to the operation of effecting surface saturation in the same manner as above described. The depth of the saturation will depend upon the 15 depth of the loosened portions. Thus where the needles 21 each penetrate substantially one-half the thickness of the board, a saturation 17 of full board thickness, as shown in Fig. 4, will result; while a shallower depth of needle penetration 20 will produce a pair of opposed spot saturated portions 23 separated by a narrow unsaturated board portion 24, as shown in Fig. 5. Properly proportioned, the Fig. 5 embodiment will give substantially the same protective, strengthening 25 and sealing properties as full depth saturation, as illustrated in Fig. 8, with the advantage of full insulating value at portion 24. Inasmuch as composition board is of a thickness of one-half inch or more, and it is desirable to keep needles 30 21 as thin as possible, the method of working inwardly from opposite faces of the board is of greater practical advantage than the Fig. 7 embodiment, as will be obvious.

While the best results are obtained by the 35 method and embodiments above described, other methods may also be employed with good results. Thus, where surface saturation is unimportant or undesirable, a deep spot saturation 25, as illustrated in Fig. 6, may be obtained to give the advantages sought. An illustrative method for obtaining this result is to preheat a limited portion of the board to be saturated, and then to force a flow of fluid waterproofing material under pressure through an outlet which is pressed against 40 the face of the board to confine the fluid discharge to a localized portion of the board with the pressure of the fluid sufficient to produce the desired penetration thereof into the board. A thinner grade or character of waterproofing than 45 50 may be used in the preferred method gives the best results in this method.

I claim:

1. A rigid composition board formed of compacted fibrous material having a plurality of 55 spaced restricted nailing portions thereof saturated with waterproofing material to a depth at least one-fourth the thickness of the board to bind together the constituent fibers of the board for tight waterproof fit with nails driven there-through, said board retaining the insulation properties and continuous fibrous character thereof substantially unimpaired throughout.

2. The construction defined in claim 1, where-in said waterproofing material is of plastic character and said nailing portion is spaced from the edge of the board.

3. The construction defined in claim 1, where-in said board is saturated at all surfaces thereof to a depth not greater than one-half the depth 70 of saturation at said restricted nailing portion.

4. A rigid composition board formed of compacted fibrous material which normally resists saturation with a plastic, said fibrous material having a plurality of spaced portions of restricted 75

5 dimensions whose porosity is greater than the remainder of the board, and plastic material penetrating said restricted porous portions to waterproof the same and bind the fibrous material together in hardened and rigidified nailing portions, said fibrous material being substantially continuous throughout the board.

10 5. A composition board formed of compacted fibrous material, having a plurality of small deep closely grouped openings therein which loosen the fibers of the board without substantially varying the continuity thereof, and plastic filling said openings and saturating the fibrous material therebetween to form a nailing portion in the 15 board completely surrounded by unsaturated fibrous material retaining the insulating properties of the board substantially unimpaired, said nailing portion being of substantially uniform hardness throughout.

20 6. The construction defined in claim 5, wherein said openings are arranged in two groups each of a depth less than one-half the thickness of the board and at opposite faces of the board to provide opposed restricted portions of deep saturation.

25 7. The construction defined in claim 5, where-

in the portions of the board adjacent each surface thereof are saturated with said plastic to a shallow depth to retain the major portion of the board unsaturated and its insulation values substantially unimpaired.

5 8. A rigid composition board formed of compacted fibrous material having an imperforate nailing portion thereof saturated with waterproofing material to bind together the constituent fibers of the board for tight waterproof fit with a nail driven therethrough, said nailing portion being of restricted size to retain the full insulating value of the board throughout the major portion thereof.

10 9. A rigid composition board formed of compacted fibrous material having at least one surface portion shallowly impregnated with waterproofing material, said board having a small portion thereof impregnated with waterproofing material to a much greater depth to uniformly 15 harden the board throughout said portion and accommodate nailing thereof without materially reducing the insulation value of the board as a whole and without substantially altering the continuity of the fibrous material.

20 25 EUGENE C. KNOBLOCK.

DISCLAIMER

2,210,321.—*Eugene C. Knoblock*, South Bend, Ind. SPOT-SATURATED COMPOSITION BOARD. Patent dated August 6, 1940. Disclaimer filed February 12, 1944, by the assignee, *Mastic Asphalt Corporation*.
